APPARATUS FOR STRIPPING INGOT MOLDS

King H. McLaurin, Duquesne, Pa.

Application October 9, 1933, Serial No. 692,886

3 Claims. (Cl. 22—95)

This invention relates to an apparatus for stripping ingot molds, and more particularly to the loosening of "big-end-up" ingots in their molds, although not limited thereto.

5 In recent years, several changes in the form of ingots and molds have been advanced, as means for improving the soundness of the ingots. One of these changes involves the reversal of the taper in the mold, making the ingot what is known as 10 being of the "big-end-up" type. Another improvement is in the form of a refractory "hot-top" to provide a sink-head or "shrink-head" on top of the ingot. These improvements are at present 15 being commonly used, either separately or in combination.

The acceptance of the "big-end-up" ingot as being decidedly superior over the product of the prior art has necessitated numerous difficulties in the stripping and handling of the ingots and 20 molds. Due to the smaller lower end of the ingot, it can no longer stand unsupported for transportation to the soaking pit or reheating furnace after it has been loosened in the mold. Numerous 25 metallurgical difficulties arise if the ingot mold is reversed on the stool, or laid down on its side.

In view of these difficulties, it has become common practice to loosen the ingot in the mold at the usual ingot stripper and to then leave it in the mold for transportation to the soaking pit, where 30 it is withdrawn and charged into the furnace. As the soaking pit cranes have tongs for lifting only, it is desirable to first pass the ingot and mold under the "stripper" for "feeling" the ingot and to force loose any "stickers".

35 The provision of a stripper or "loosener" for "big-end-up" ingots ordinarily involves a heavy investment in several especially designed cranes. Stripper cranes for the old type "small-end-up" molds cannot be used.

40 A number of recent developments provide a pair of powerful tongs which seize the ingot by the hot-top and pull it out, while the mold is held down by the side links of the crane. If a tile "hot-top" is used, the tongs crush through the tile 45 and bite into the solidified steel. If a brick-lined casing is used for a "hot-top", the casings are usually removed at the open-hearth plant before the ingots are transported to the "stripper" or "loosener".

50 It is often desirable to loosen "big-end-up" ingots without "hot-tops", and in this event another stationary type of "loosener" has heretofore been necessary. In this device, a powerful plunger rises from a mechanism below the level 55 of the floor on which the mold cars are disposed

and engage a closure plug set in an aperture in the bottom of the ingot mold. A pair of side links engage the lugs on the mold to hold it down when the plunger rises. In numerous steel plants complicated overhead mechanism is used.

60 Another advance has been to strip "big-end-up" ingots without hot-tops by setting a pin on the ingot mold stool to engage the plug in the bottom of the mold and thus hold the ingot up out of the mold a sufficient distance so that the tongs of the soaking pit cranes can lift the ingots therefrom.

65 One object of the present invention is the provision of a novel apparatus for stripping ingots, and particularly those of the "big-end-up" variety in a highly efficient and inexpensive manner.

70 Another object is to provide a novel mold having a highly improved stool construction which, when used therewith, necessitates only the use 75 of a crane, and thus obviates the necessity of complicated machinery and the burden of its maintenance.

75 These and further objects will be apparent after referring to the drawings, in which:

80 Figure 1 is a sectional elevation of the apparatus of the invention.

85 Figure 2 is a view similar to Figure 1 of the apparatus in another stage of operation.

Figure 3 is a view similar to Figures 1 and 2, 85 but showing the apparatus in a third step of operation.

Figure 4 is a plan of the novel stool of the invention.

90 Figure 5 is a plan of the stool in another stage of operation.

95 Referring more particularly to the drawings, the numeral 2 designates an ingot mold having a bottom portion 2^a of smaller area than the upper portion 2^b, in order to cast ingots of the "big-end-up" type. The ingot mold 2 is provided with a tapered aperture 2^c in the bottom thereof and has on its outer side lugs 2^d and 2^e for enabling its handling with a crane. A tapered plug 3 is adapted to seat in the aperture 2^c of 100 the ingot mold in such manner as to project beyond the bottom thereof, as at 3^a.

An ingot 4 of the "big-end-up" type is shown within the ingot mold 2 and extending upwardly 105 therefrom, as at 4^a, the usual "hot-top" having previously been removed.

110 The novel ingot mold stool of the invention is generally indicated at 5, and is provided with a central aperture 5^a, and an enlarged slot 5^b arranged transversely with respect to the axis of the

aperture 5^a and in communication therewith. A plate 6 is adapted to slide in the slot 5^b and to be moved into a position covering the aperture 5^a.

The usual crane 9 grips the ingot mold 2 by means of its cooperating lugs 2^e and 2^f, and a hooked-rod 7 is adapted to be inserted in an aperture 6^a of the plate 6 for moving it in the slot 5^b.

In operation, a plurality of stools 5 are disposed on ingot mold cars 8 with the plate 6 remotely disposed in the slot 5^b with respect to the aperture 5^a. Ingot molds 2 are placed on each of the ingot mold buggies 8 with the plug 3 in position and extending, as at 3^a, into the aperture 5^a of the stool. After the ingots have been cast and permitted to solidify, the ingot molds are raised by means of the crane 9, the hooked-rod 7 inserted in the apertures 6^a of the various plates 6 and the plates moved over the apertures 5^a. The ingot molds 2 are lowered and the extended portion 3^a of each of the plugs 3 is permitted to rest on a plate 6, which forces the ingot upwardly in the mold.

The mold cars 8 are then transported to a position adjacent the usual soaking pit, or reheating furnace, and a conventional soaking pit crane is used to remove them from the mold and place them therein.

While I have shown and described one specific embodiment of my invention, it will be understood that I do not wish to be limited exactly thereto, since various modifications may be made with-

out departing from the scope of my invention, as defined in the following claims.

I claim:

1. Apparatus for stripping an ingot mold having a smaller bottom than the upper portion thereof, comprising a plug disposed in an aperture in said mold, and adapted to protrude therefrom, a stool for said ingot mold having an aperture into which said plug is adapted to extend, said stool having an enlarged slot in communication with said aperture, and a plate slidable in said slot and adapted to cover said aperture. 80

2. Apparatus for stripping an ingot mold having a smaller bottom than the upper portion thereof, comprising a plug disposed in an aperture in said mold and adapted to protrude therefrom, a stool for said ingot mold having an aperture into which said plug is adapted to extend, said stool having an enlarged slot in communication with said aperture, and a plate slidable in said slot and adapted to cover said aperture, said ingot mold having lugs thereon for enabling its handling. 85

3. Apparatus for stripping an ingot mold having an aperture in its bottom, comprising a plug 100 in said aperture which is adapted to protrude therefrom, a stool having an aperture into which said plug is adapted to extend, said stool having a slot in communication with said aperture, and a plate movable in said slot and adapted to cover said aperture. 90
